For Messrs
N. B. Smith
Alb. M. Mahon

Inventor

Charles White
by his Atty
A. B. Smith

United States Patent Office.

CHARLES WHITE, OF BLADENSBURG, MARYLAND.

Letters Patent No. 74,183, dated February 4, 1868.

IMPROVEMENT IN PLOUGHS.

The Schedule referred to in these Letters Patent and making part of the same.

TO ALL WHOM IT MAY CONCERN:

Be it known that I, CHARLES WHITE, of Bladensburg, in the county of Prince George, and State of Maryland, have invented certain new and useful Improvements in Ploughs; and I do hereby declare the following to be a full, clear, and exact description of the same, reference being had to the accompanying drawings, in which—

Figure 1 is a perspective view of a plough embracing my improvements.

Figure 2 is a vertical longitudinal section through the beam and its pivotal support, showing the arrangement of the yielding draught-rod and spring; and

Figure 3 is a similar section of the beam, showing a different application of pivot and spring.

Similar letters of reference denote corresponding parts in all the figures.

My invention consists, first, in a novel arrangement of devices for effecting the double adjustment, that is to say, the vertical and horizontal or lateral adjustment of the plough-beam relative to the plough; second, in the manner of pivoting the beam through a forked pivotal standard, or its equivalent, mounted in a horizontal lug or flange of the mould-board; third, in a novel form or construction of the plough-beam; fourth, in the employment of a yielding tension or draught-rod passing lengthwise centrally through the beam; and fifth, in the employment of a spring, in combination with the draught-rod, whereby the latter is made to yield and relieve the strain upon the team and plough in case the latter strikes an obstruction, as hereinafter explained.

To enable others to understand and use my invention, I will proceed to describe the same with reference to the drawings, in which A represents the mould-board, B the point, C the land-side, and D the handles, which parts are combined in the usual manner, and each of which may be of any usual or desired construction, except that the mould-board, or, if preferred, the land-side, is extended upward, and is provided with a horizontal flange or lug, a, which is perforated to receive and form a bearing for the pivotal support of the plough-beam. E is the beam, which is cast or otherwise formed in one piece, and is provided upon its opposite sides with semi-cylindrical ribs or corrugations running lengthwise of the beam, and arranged or located alternately upon opposite sides thereof, in the manner represented in the drawing. These alternating semi-tubes or corrugations perform the double function of strengthening or stiffening the beam, thereby admitting of the employment of a lighter beam than those in ordinary use, and at the same time affording bearings for the reception and proper support of the draught or tension-rod F passing lengthwise through the same. The beam E is mounted in an upright standard or pivotal support, G, which has its bearings in the lug a of the mould-board, and which may be forked to receive the beam, as represented in figs. 1 and 2, or squared and passing through a slot or perforation in the beam, as shown in fig. 3. In this latter construction the slot or perforation in the beam should be enlarged or elongated at the top, to admit of the vertical adjustment of the beam hereinafter provided for. In rear of the pivotal support, or at any other suitable point in its length, the beam is provided with a drum, or a cylindrical or partial cylindrical socket, H, which may be cast in one piece with, or otherwise rigidly united to, the beam, and adapted to receive a spring, either of rubber, or a coiled or other suitable form of metal spring, to which the tension or draught-rod is connected, as shown in figs. 2 and 3. The rear end of the drum is left open to receive the spring, and may be closed after the spring and rod are properly adjusted in the drum, by means of a removable head, h, or, if preferred, the head may be made in the form of a close-fitting plunger, attached to the rear end of the draught-rod, for the purpose of excluding dirt, which would interfere with the free action of the spring in the operation of the plough. The rear end of the beam is provided with a slot or perforation, e, through which, by means of a set-screw, or bolt and nut, said rear end of the beam is connected to the upright slotted arm of an angle-iron, I, the horizontal arm of which is connected in a similar manner to a slotted transverse bar, J, attached at its opposite ends to the rear inner faces of the land-side and mould-board, or to the plough-handles, as may be preferred. The slot j in bar J should be made in the arc of a circle, of which the pivotal support G is the centre, so that the lateral adjustment of the beam may be effected without cramping or binding the adjusting-devices; and the opposing faces of the angle-iron, beam, and transverse bar may be ribbed, if desired, to prevent slipping of the parts when properly adjusted.

The manner of effecting the adjustment of the beam and plough so as to cause the latter to take more or

less land, and for varying the depth of the furrow, will be understood without further description. The draught of the team, instead of being applied directly to the forward end of the beam, in the usual manner, is applied to the forward end of the tension or draught-rod F, at F', and said rod, through its spring-connection with the beam, in the manner explained, allows the plough to yield in the event of its striking a large stone or other obstruction, thereby obviating, to a great extent, the strain upon the team, and the danger of breaking the plough-point consequent upon the striking of such obstruction by ploughs constructed in the usual manner.

Having now described my invention, what I claim as new, and desire to secure by Letters Patent, is—

1. The angle-iron I, in combination with the slotted transverse bar J, and the rear end of the plough-beam, for effecting the double adjustment of the latter, in the manner described.
2. The pivotal support G of the plough-beam E, in combination with the perforated horizontal flange or lug a, on the mould-board, as described.
3. The plough-beam, provided with tubular or semi-cylindrical ribs or corrugations, substantially as described.
4. The yielding tension or draught-rod, passing centrally through, or having an equivalent arrangement relative to, the beam, as described.
5. The yielding draught-rod, in combination with the spring, operating as described.
6. The drum or socket, formed in or attached to the beam, in combination with the spring and draught-rod, as described.

In testimony whereof, I have hereunto subscribed my name, this ninth day of January, 1868.

CHAS. WHITE.
